UNITED STATES PATENT OFFICE

2,652,952

LIQUID SOAP DISPENSER

Douglas T. Mowbray, Waterloo, Iowa

Application January 26, 1952, Serial No. 268,380

15 Claims. (Cl. 222—180)

1

My invention relates to improvements in dispensing devices for liquids and the like and more particularly to a non-refillable liquid container for use therewith.

The disclosures hereinafter made relative to the liquid container and its cooperation with the dispenser apparatus represent an improvement over the liquid soap dispenser device disclosed in my Patent No. 2,628,744, issued Feb. 17, 1953.

In the manufacture and sale of dispensing devices such as for lubricants, liquid soap and the like, it has long been a practice in many instances that a particular dispensing apparatus is designed to dispense a particular brand of liquid material which is packaged in a suitable container for use with such apparatus. Quite generally the container bears a trade-mark name certifying to the character and quality of the material being dispensed so that the user has the assurance as to the identity of such material as represented. It is expected that when such containers are emptied, that they will be refilled with a liquid identical to that originally contained therein or a new like full container will be used to replace the depleted one. Such expectations on the part of manufacturers of dispensers and containers with a particular liquid therefore, is not without just cause as the assurance to the purchaser and user that he is receiving a particular brand of clean unadulterated liquid of the particular type, quality and character concerned is of primary importance.

The use of dispensers having easily refillable containers has made it possible for persons to refill the same with cheap and inferior liquids or fraudulent substitution of grades and brands that when done on containers carrying well established trade-marks and names, is in effect a fraud on the purchasers and users by the trading on the good will and reputation of the original contents of the container.

With the above observations in mind, it is the general aim of my invention to provide with a dispenser apparatus for liquids such as liquid soap and the like, a liquid container that cannot be refilled so that a new container must be used after the original has been emptied.

More specifically, the object of my invention is to provide a liquid dispensing device of the above class which is constructed to operate in cooperation only with an exclusive type of container and to thereby prevent unauthorized containers from being used therewith.

A further object of the invention is to provide

2

a container of standard proportions, but which is specifically equipped to be received by a dispensing apparatus, that will not successfully receive or support containers not similarly equipped.

5 Still a further object of this invention is to provide a liquid soap dispensing apparatus having the characteristics above described that will deposit a desired amount of liquid soap on the hands of the user without requiring the touching 10 of the device by the hands.

A still further object of this invention is to provide a liquid soap dispenser and container therefor of the above class that is operated by the foot of the user.

15 A further object of this invention is to provide a liquid soap dispenser having an exclusive container as above described which can be quickly and easily attached to or removed therefrom.

These and other objects will be apparent to 20 those skilled in the art.

My invention consists in the construction, arrangement, and combination of the various parts of the device, whereby the objects contemplated are attained as hereinafter more fully set forth, 25 pointed out in my claims, and illustrated in the accompanying drawings, in which:

Fig. 1 is a perspective view of my new liquid soap foot operated dispenser,

Fig. 2 is a side elevational view of the container for liquid to be dispensed,

Fig. 3 is an enlarged longitudinal section view of the container taken on the line 3—3 of Fig. 2,

Fig. 4 is an enlarged longitudinal section view of the dispenser apparatus with container attached,

Fig. 5 is a cross-sectional view taken on the line 5—5 of Fig. 4, and

Fig. 6 is a cross-sectional view taken on the line 6—6 of Fig. 4.

40 Referring to the drawings I have used the numeral 10 to designate a vertical base or plate member for my dispenser apparatus that is designed to be mounted on a wall 12 by any suitable means and preferably by screws 14 as illustrated in Fig. 1. Extending rearwardly at substantially right angles from the top portion of the base member 10 and formed integrally therewith is a head section 16 which is provided with a vertical opening therethrough that varies

45 in diameter at different points as I will now describe. This opening at the bottom portion of the head section 16 has the internal circumscribing threads 18 as shown in Fig. 4 which are adapted to receive the threaded neck portion 55 of any suitable standard size container 20. Above

the threads 18 this opening is concentrically reduced to form the horizontal annular shoulder 22 and vertical annular wall 24. A further concentrical reduction in the opening above the wall 22 forms the horizontal annular shoulder 26 and the resulting vertical annular wall 28 as shown in Fig. 4 which extends towards but not to the top of said head section. Above the upper limits of the wall 28 the opening is further concentrically reduced and extends upwardly therefrom through the top of the head section 16.

A passageway 30 in the head section 16 communicates at one end with the vertical opening in said head section through the upper portion of the wall 28, and at its other end with the upper portion of base member 10. A manually operable valve means 32 may be connected to the passageway 30 as shown in Fig. 4. A conduit 34 extends vertically downwardly through the base 10 and communicates at its upper end with the passageway 30. The numeral 36 designates a soap dispensing conduit swivelly arranged in the opening at the top of the head section by means of the nipple 38 and gland nut 40 as shown in Fig. 4. This conduit 36 extends rearwardly and upwardly a substantial distance and then is curved to extend downwardly at its discharge or spout end (Fig. 1). By this construction, any dripping of the liquid soap after using this device is substantially eliminated, since liquid in the conduit 36 will be carried by gravity away from the spout when this device is not in operation. A resilient foot operated bellows or pump means 42 is connected by the flexible conduit 44 to the conduit 34 in the base 10 and a suitable valve means (not shown) is imposed in the bellows 42 in cooperation with conduit 44.

Referring now to the container 20 as shown in Figs. 3 and 4 it has been previously indicated that it is of the non-refillable type and this is accomplished by the following construction. The top of this container is enclosed and is provided with a central opening in which I place the one-way ball valve 48 that is in direct alignment with the lower end of the swivel conduit 36. A vertical tube member 50 communicates at its top with the valve 48 and extends downwardly within the container to the bottom thereof. It will be observed that the bottom of the tube 50 is angled as at 52 to afford a means of ingress thereto for liquid 54 that is in the container. Thus constructed, liquid 54 can pass upwardly through the valve 48 as will be later described, but it will be impossible to refill the container by trying to pass liquid downwardly through the valve. The top of the neck of this container presents a corrugated outline in longitudinal cross-section (Fig. 3) by an arrangement of ridges and a depression. This is accomplished by an outer peripheral annular ridge 56 and by a second annular ridge 58 reduced in size and concentrically arranged relative to ridge 56 which creates the annular depressions 60 and 62 with the depression 60 being intermediate the ridges 56 and 58 and the depression 62 being intermediate the ridge 56 and the valve 48. One or more openings 64 are made transversely through the ridge 58 and preferably I show two oppositely disposed theron relative to the center valve opening in the container. A suitable removable cap 66 is provided for the container when it is being stored or shipped or otherwise not connected to the dispenser when containing a liquid soap.

In order to properly seal the container when it is screwed into the dispenser, I provide the

cylindrical shaped gasket 68 of rubber or the like, that is arranged within the head section 16 and engages the corrugated top of the container. This gasket is reduced in diameter at its upper portion which creates a shoulder so that it provides an air tight seal within the head 16 by engaging the wall 24, the shoulder 26 and the wall 28, as shown in Fig. 4. The top of this gasket, however, will be spaced below the upper limits of the head section wall 28 to form the chamber 29. The bottom of this gasket 68 presents a surface of alternating annular ridges and depressions similar to the neck of the container, but of such diameters that the respective ridges on the gasket will be complementary to depressions in the container neck and depressions in the gasket will be complementary to ridges on the container when the same are placed in juxtaposition. This is shown in Fig. 4 by the outer annular ridge 70 on the gasket, the concentrical smaller ridge 72, the annular depression 74 intermediate the ridges 70 and 72, and the center depression 76. The gasket is provided with a transverse center opening or passageway 78 that terminates at the bottom in the depression 76 and oppositely disposed in the gasket relative to the center opening 78 and extending in the same direction as this opening are the two relatively small air passageways 80 that communicate at the bottom with the depression 74. It will be observed that when this gasket is arranged within the head section 16 and the container 20 is screwed therein as described and shown in Fig. 4, the depression 74 in the gasket is constructed so as not to snugly engage the ridge 58 of the container whereby a portion of the depression 74 becomes in effect an air chamber. It is with this chamber that the air passageways 80 communicate and it will be observed that the openings 64 in the ridge 58 of the container also communicate with this chamber as illustrated in Fig. 4.

A short conduit 82 that serves as a lower continuation of tube 36, is frictionally secured within the center passageway 78 of the gasket. This conduit carries external threads to receive the bottom of the soap dispensing conduit 36 and the upper end thereof is crimped as at 84 (Fig. 5) so that the lower end of conduit 36 will easily pass over it. Within the conduit 82 is a one-way ball check valve means 86 that will allow liquid to pass upwardly therethrough but not downwardly. This prevents any liquid draining back in the conduit 36 after use, and also prevents the remaining liquid in conduit 36 from draining out when the soap cartridge is removed or replaced.

Thus constructed and arranged, this dispenser will operate in the following manner. Delivery of liquid soap at the spout end of conduit 36 is accomplished by depressing the bellows 42 with the foot. When this is done, air is forced through conduit 34, thence through passageway 30 into chamber 29, thence through air passageways 80 in the gasket and thence through the openings 64 in the container to the interior of the container above the surface of the liquid 54. The resulting pressure on the liquid will cause it to pass upwardly through the tube member 50, through the valves 48 and 86 and out of the conduit 36. Upon release of pressure on the bellows, it will expand and relieve air pressure on the liquid within the container to stop movement of the liquid to the spout. For an additional supply of soap, the action above described is merely repeated. By adjustment of the valve 32, the

amount of liquid soap delivered at the spout can be easily adjusted.

It will be appreciated that the construction of the container 20 with the one-way ball valve 48 makes the container non-refillable so that once it is emptied, it must be discarded. To assure that a similar full container will be used to replenish the soap supply for reasons previously pointed out, it will be observed that the arrangement and cooperation between the container neck and gasket as disclosed and described is essential. By the arrangement of complementary alternating ridges and depressions in the container neck and gasket bottom, there is no leakage of air through the gasket into the container. To use any other type container against the corrugated gasket bottom would create enough air leakage to render the dispenser inoperable. It is further observed that the formation of the air chamber between the top of the depression 74 in the gasket and the top of the ridge 58 on the container makes it possible to thread the container into the head section without having to align the passageways 80 with the openings 64. This is true since any air entering this chamber under pressure will travel therein until it reaches an escape point afforded by the openings 64. Thus, it is apparent that while the container may be of standard proportion and have a neck portion of a standard diameter, it is specially equipped and constructed to be received by the dispensing unit, which itself has features of a special nature so that it will not successfully receive or support containers not similarly equipped as herein described.

Some changes may be made in the construction and arrangement of my liquid soap dispenser without departing from the real spirit and purpose of my invention, and it is my intention to cover by my claims, any modified forms of structure or use of mechanical equivalents which may be reasonably included within their scope.

I claim:

1. In a liquid soap dispenser, a base member, a head section secured to said base member, said head section provided with an opening therethrough, a cylindrical gasket in said opening, said gasket provided with a center opening concentrical with said head section opening, an air passageway through said gasket parallel to and spaced from said opening therein, a discharge conduit swivelly secured to said head section so that a portion thereof extends into said head section opening and into the center opening of said gasket, a liquid container capable of being removably attached to and solely supported by said head section, a tube member extending from the inside bottom of said container upwardly to the top thereof, a one-way valve in the top of said tube member, said one-way valve in communication with the center opening in said gasket, an air opening in said container in communication with the air passageway in said gasket, and a conduit in said base member communicating at one end with the air passageway in said gasket and at its other end designed to communicate with a source of forced air.

2. A device as defined in claim 1, with a one-way valve means disposed in the center opening of said gasket.

3. In a liquid soap dispenser, a base member, a head section secured to said base member, said head section provided with an opening therethrough, a cylindrical gasket in said opening, said gasket provided with a center opening concen-

trical with said head section opening, one end of said gasket presenting a surface of alternating concentrically arranged ridges and depressions, an air passageway through said gasket parallel to and spaced from said opening therein, a discharge conduit swivelly secured to said head section so that a portion thereof extends into said head section opening and into the center opening of said gasket, a liquid container capable of being removably attached to and solely supported by said head section, said container at its attaching point to said head section presenting a surface of alternating concentrically arranged ridges and depressions constructed so that the ridges on said container and gasket respectively will nest in depressions on the other to form an air tight seal therebetween, a tube member extending from the inside bottom of said container upwardly to the top thereof, a one-way valve in the top of said tube member, said one-way valve in communication with the center opening in said gasket, an air opening in said container in communication with the air passageway in said gasket, and a conduit in said base member communicating at one end with the air passageway in said gasket and at its other end designed to communicate with a source of forced air.

4. In a liquid soap dispenser, a base member, a head section secured to said base member, said head section provided with an opening therethrough, a cylindrical gasket in said opening, said gasket provided with a center opening concentrical with said head section opening, one end of said gasket presenting a surface of alternating concentrically arranged ridges and depressions, a discharge conduit swivelly secured to said head section so that a portion thereof extends into said head section opening and into the center opening of said gasket, a liquid container capable of being removably attached to and solely supported by said head section, said container at its attaching point to said head section presenting a surface of alternating concentrically arranged ridges and depressions, a discharge conduit swivelly secured to said head section so that a portion thereof extends into said head section opening and into the center opening of said gasket, a liquid container capable of being removably attached to and solely supported by said head section, said container at its attaching point to said head section presenting a surface of alternating concentrically arranged ridges and depressions constructed so that the ridges on said container and gasket respectively will nest in depressions on the other to form an air tight seal therebetween and further constructed so that one ridge on said container does not occupy the entire area in depth of the corresponding depression in said gasket whereby an air chamber is formed, an air passageway through said gasket communicating with said air chamber, a tube member extending from the inside bottom of said container upwardly to the top thereof, a one-way valve in the top of said tube member, said one-way valve in communication with the center opening in said gasket, an air opening in one of the ridges in said container communicating with said air chamber, and a conduit in said base member communicating at one end with the air passageway in said gasket and at its other end designed to communicate with a source of forced air.

5. In a dispensing apparatus for liquid soap and the like, a base member adapted to be mounted on a wall or similar support, a head section extending from said base member and provided with a vertical opening therethrough, said vertical opening being progressively larger from top to bottom by a series of steps and shoulders, a cylindrical gasket having progressively larger diameters from top to bottom by a series of steps and shoulders and adapted to be arranged within said vertical openings so as to be complementary with the steps and shoulders therein to form

an air tight seal, said gasket provided with a central vertical opening registering with the opening in said head section, an air passageway through said gasket parallel to and spaced from said opening therein, a discharge conduit swivelly secured to said head section so that a portion thereof extends into said head section opening and into the center opening of said gasket, a liquid container capable of being removably attached to and solely supported by said head section, a tube member extending from the inside bottom of said container upwardly to the top thereof, a one-way valve in the top of said tube member, said one-way valve in communication with the center opening in said gasket, an air opening in said container in communication with the air passageway in said gasket, and a conduit in said base member communicating at one end with the air passageway in said gasket and at its other end designed to communicate with a source of forced air.

6. In a dispensing apparatus for liquid soap and the like, a base member adapted to be mounted on a wall or similar support, a head section extending from said base member and provided with a vertical opening therethrough, said vertical opening being progressively larger from top to bottom by a series of steps and shoulders, a cylindrical gasket having progressively larger diameters from top to bottom by a series of steps and shoulders and adapted to be arranged within said vertical openings so as to be complementary with the steps and shoulders therein to form an air tight seal, said gasket provided with a central vertical opening registering with the opening in said head section, the larger end of said gasket presenting a surface of alternating concentrically arranged ridges and depressions, a discharge conduit swivelly secured to said head section so that a portion thereof extends into said head section opening and into the central opening in said gasket, a liquid container removably attached to and solely supported by the bottom portion of the opening in said head section, said container at its attaching point to said head section presenting a surface of alternating concentrically arranged ridges and depressions constructed so that the ridges on said container and gasket respectively will nest in depressions on the other to form an air tight seal therebetween, an air passageway through said gasket, an air opening in said container communicating with said air passageway, and a conduit in said base member communicating at one end with said air passageway and at the other end with a source of forced air.

7. In a dispensing apparatus for liquid soap and the like, a base member adapted to be mounted on a wall or similar support, a head section extending from said base member and provided with a vertical opening therethrough, said vertical opening being progressively larger from top to bottom by a series of steps and shoulders, a cylindrical gasket having progressively larger diameters from top to bottom by a series of steps and shoulders and adapted to be arranged within said vertical openings so as to be complementary with the steps and shoulders therein to form an air tight seal, said gasket provided with a central vertical opening registering with the opening in said head section, the larger end of said gasket presenting a surface of alternating concentrically arranged ridges and depressions, a discharge conduit swivelly secured to said head section so that a portion

thereof extends into said head section opening and into the central opening in said gasket, a liquid container removably attached to and solely supported by the bottom portion of the opening in said head section, said container at its attaching point to said head section presenting a surface of alternating concentrically arranged ridges and depressions constructed so that the ridges on said container and gasket respectively will nest in depressions on the other to form an air tight seal therebetween, and further constructed so that one ridge on said container does not occupy the entire area in depth of the corresponding depression in said gasket whereby an air chamber is formed, an air passageway through said gasket communicating with said air chamber, an air opening through one of the ridges in said container communicating with said air chamber, and a conduit in said base member communicating at one end with said air passageway and at the other end with a source of forced air.

8. In a dispensing apparatus for liquid soap and the like, a base member adapted to be mounted on a wall or similar support, a head section extending from said base member and provided with a vertical opening therethrough, said vertical opening being progressively larger from top to bottom by a series of steps and shoulders, a cylindrical gasket having progressively larger diameters from top to bottom by a series of steps and shoulders and adapted to be arranged within said vertical openings so as to be complementary with the steps and shoulders therein to form an air tight seal at the sides, and the top of said gasket being spaced from the uppermost shoulder within the head section opening to form an air chamber, said gasket provided with a central vertical opening registering with the opening in said head section, an air passageway through said gasket parallel to and spaced from said opening therein, a discharge conduit swivelly secured to said head section so that a portion thereof extends into said head section opening and into the center opening of said gasket, a liquid container capable of being removably attached to and solely supported by said head section, a tube member extending from the inside bottom of said container upwardly to the top thereof, a one-way valve in the top of said tube member, said one-way valve in communication with the center opening in said gasket, an air opening in said container in communication with the air passageway in said gasket, and a conduit in said base member communicating at one end with said air chamber and at its other end designed to communicate with a source of forced air.

9. In a dispensing apparatus for liquid soap and the like, a base member adapted to be mounted on a wall or similar support, a head section extending from said base member and provided with a vertical opening therethrough, said vertical opening being progressively larger from top to bottom by a series of steps and shoulders, a cylindrical gasket having progressively larger diameters from top to bottom by a series of steps and shoulders and adapted to be arranged within said vertical openings so as to be complementary with the steps and shoulders therein to form an air tight seal at the sides, and the top of said gasket being spaced from the uppermost shoulder within the head section opening to form an air chamber, said gasket

provided with a central vertical opening registering with the opening in said head section, the larger end of said gasket presenting a surface of alternating concentrically arranged ridges and depressions, a discharge conduit swivelly secured to said head section so that a portion thereof extends into said head section opening and into the central opening in said gasket, a liquid container removably attached to and solely supported by the bottom portion of the opening in said head section, said container at its attaching point to said head section presenting a surface of alternating concentrically arranged ridges and depressions constructed so that the ridges on said container and gasket respectively will nest in depressions on the other to form an air tight seal therebetween, an air passageway through said gasket, an air opening in said container communicating with said air passageway, and a conduit in said base member communicating at one end with said air chamber and at the other end with a source of forced air.

10. In a dispensing apparatus for liquid soap and the like, a base member adapted to be mounted on a wall or similar support, a head section extending from said base member and provided with a vertical opening therethrough, said vertical opening being progressively larger from top to bottom by a series of steps and shoulders, a cylindrical gasket having progressively larger diameters from top to bottom by a series of steps and shoulders and adapted to be arranged within said vertical openings so as to be complementary with the steps and shoulders therein to form an air tight seal at the sides, and the top of said gasket being spaced from the uppermost shoulder within the head section to form an air chamber, said gasket provided with a central vertical opening registering with the opening in said head section, the larger end of said gasket presenting a surface of alternating concentrically arranged ridges and depressions, a discharge conduit swivelly secured to said head section so that a portion thereof extends into said head section opening and into the central opening in said gasket, a liquid container removably attached to and solely supported by the bottom portion of the opening in said head section, said container at its attaching point to said head section presenting a surface of alternating concentrically arranged ridges and depressions constructed so that the ridges on said container and gasket respectively will nest in depressions on the other to form an air tight seal therebetween, and further constructed so that one ridge on said container does not occupy the entire area in depth of the corresponding depression in said gasket whereby an air chamber is formed, an air passageway through said gasket communicating at one end with said first mentioned air chamber and at its other end with said second mentioned air chamber, an air opening through one of the ridges in said container communicating with said second mentioned air chamber, and a conduit in said base member communicating at one end with said first mentioned air chamber.

11. In a dispensing apparatus for liquid soap and the like, a base member adapted to be mounted on a wall or similar support, a head section extending from said base member and provided with a vertical opening therethrough, said vertical opening being progressively larger from

top to bottom by a series of steps and shoulders, a cylindrical gasket having progressively larger diameters from top to bottom by a series of steps and shoulders and adapted to be arranged within 5 said vertical openings so as to be complementary with the steps and shoulders therein to form an air tight seal at the sides and the top of said gasket being spaced from the uppermost shoulder within the head section opening to form an air 10 chamber, said gasket provided with a central vertical opening registering with the opening in said head section, the larger end of said gasket presenting a surface of alternating concentrically arranged ridges and depressions, a discharge conduit swivelly secured to said head section so that a portion thereof extends into said head section opening and into the central opening in said gasket, a liquid container removably attached to and solely supported by the bottom portion 15 of the opening in said head section, said container at its attaching point to said head section presenting a surface of alternating concentrically arranged ridges and depressions constructed so that the ridges on said container and gasket respectively will nest in depressions on the other to form an air tight seal therebetween, and further constructed so that one ridge on 20 said container does not occupy the entire area in depth of the corresponding depression in said gasket whereby an air chamber is formed, an air passageway through said gasket communicating at one end with said first mentioned chamber and at its other end with said second mentioned air chamber, an air opening in said container 25 communicating with said second mentioned air chamber, and a conduit in said base member communicating at one end with said first mentioned air chamber and at the other end with a source of forced air.

12. A device as defined in claim 11 with a one-way valve means in the central opening of said gasket.

13. In a dispensing apparatus for liquid soap and the like having a head section provided with a vertical opening therethrough, said vertical opening being progressively larger from top to bottom by a series of steps and shoulders, a cylindrical gasket having progressively larger diameters from top to bottom by a series of steps and shoulders and adapted to be arranged within 45 said vertical openings so as to be complementary with the steps and shoulders therein to form an air tight seal, said gasket provided with a central vertical opening registering with the opening in said head section, said gasket provided with an air passageway that communicates with the atmosphere, a liquid container capable of being removably attached to and solely supported by said head section, a tube member extending from the inside bottom of said container upwardly to the top thereof, a one-way valve in the top of said tube member, said one-way valve in communication with the center opening in said gasket, an air opening in said container in 50 communication with the air passageway in said gasket, and a conduit in said base member communicating at one end with the air passageway in said gasket and at its other end designed to communicate with a source of forced air.

14. In a liquid soap dispenser having a head section provided with an opening therethrough, a cylindrical gasket in said opening, said gasket provided with a center opening concentrical with said head section opening, one end of said 55 gasket presenting a surface of alternating con-

centrically arranged ridges and depressions, said gasket provided with an air passageway that communicates with the atmosphere, a liquid container capable of being removably attached to and solely supported by said head section, said container at its attaching point to said head section presenting a surface of alternating concentrically arranged ridges and depressions constructed so that the ridges on said container and gasket respectively will nest in depressions on the other to form an air tight seal therebetween, a tube member extending from the inside bottom of said container upwardly to the top thereof, a one-way valve in the top of said tube member, said one-way valve in communication with the center opening in said gasket, an air opening in said container in communication with the air passageway in said gasket, and a conduit in said base member communicating at one end with the air passageway in said gasket and at its other end designed to communicate with a source of forced air.

15. In a dispensing apparatus for liquid soap and the like having a head section provided with a vertical opening therethrough, said vertical opening being progressively larger from top to bottom by a series of steps and shoulders, a cylindrical gasket having progressively larger diameters from top to bottom by a series of steps and shoulders and adapted to be arranged within said vertical openings so as to be complemen-

tary with the steps and shoulders therein to form an air tight seal at the sides, and the top of said gasket being spaced from the uppermost shoulder within the head section opening to form an air chamber, said gasket provided with a central vertical opening registering with the opening in said head section, said gasket provided with an air passageway that communicates with said chamber, a liquid container capable of being removably attached to and solely supported by said head section, a tube member extending from the inside bottom of said container upwardly to the top thereof, a one-way valve in the top of said tube member, said one-way valve in communication with the center opening in said gasket, an air opening in said container in communication with the air passageway in said gasket, and a conduit in said base member communicating at one end with said air chamber and at its other end designed to communicate with a source of forced air.
